CURTAIN SUPPORT

Filed Aug. 26, 1929

UNITED STATES PATENT OFFICE

RICHARD R. BRUCKNER, OF NEW YORK, N. Y.

CURTAIN SUPPORT

Application filed August 26, 1929. Serial No. 388,325.

This invention relates to improvements in curtain supports and the principal object is the provision of a device which includes supporting rails or tracks upon which curtain holding members or brackets are mounted so as to move with a minimum amount of friction and with a minimum expenditure of power.

A further object of this invention includes an improvement in a supporting bracket for such a device.

The drawings show a preferred embodiment of my invention but it is to be expressly understood that changes may be made in practice within the scope of the claims without digressing from my invention. In the drawings—

Figure 1 represents a side view of an assembly constructed to embody my invention.

Figure 2 is a bottom plan view with parts in section and portions omitted to facilitate the disclosure.

Figure 3 is a vertical cross-section, taken through Figure 1.

Figure 4 is a side elevation of one form of bracket and supporting pulley.

Figure 5 is a side elevation of one of the master brackets.

Figure 6 is a side view of a modification showing a different form of tensioning means for the cable.

Referring now to the drawings, the numeral 1 designates a suitable elongated support which is shown in the form of a pipe and which is provided at intervals with means such as bolt 2 and spacing sleeves 3 for supporting the elongated track members 4. These track members are of general rectangular shape in cross section, hollow and having a longitudinal slot or opening 5 extending into and through the bottom side thereof. The edges 6 of the bottom member are turned inwardly at an acute angle so as to provide supporting and locking means for the rails 7, which extend longitudinally of the track members, one on each side of the slot or opening 5 and which have the laterally extending flange or shoulder 8 against which the roller members 9 of the supporting brackets rest and run. It is to be noted

that the rails terminate in an edge 9' with which the rollers engage so as to provide minimum amount of frictional contact between the parts.

These rollers 9 are rotatably mounted upon the horizontal axle 10, positioned in two side lugs 11 of the socket member 12 formed on the upper end of the bracket member 13. This bracket member is curved as shown to provide sufficient clearance for the roller member 9 and extends downwardly a sufficient distance to properly receive the fastening means for the curtain, slot or aperture 14 being provided in the lower portion of said bracket member for that purpose.

The master bracket member is illustrated in Figure 5 and is practically a duplicate of bracket member 13 as far as the lugs 11 and socket 12 are concerned. These parts are joined by a substantial body portion 16 provided with means 17 for attachment to the drawing cord or cable 18. The lower portion of this body member is provided with the aperture or slot at 19 to receive the curtain fastening means. In order to limit the travel of the master bracket members, stops 15 are provided at the inner ends of track members 4. These stops are shown as strips which extend across the slot or opening 5 in track members 4.

As shown in Figure 1, I provide a motor 20 which is suspended at one end of the track members 4 and which forms a tensioning means for the cable 18. The motor 20 is mounted in a receptacle 21 which is provided with grooved or channeled guide shoes 22 which are adapted to be mounted on and slide between guide bars 23 which are T shaped in cross section. The motor 20 is operatively connected to the pulleys 24 by means of worm gears 25 and 26 and drum 27. Idler pulleys 24' are provided adjacent one pulley 24. The gear 26 and drum 27 are mounted on horizontal axle 28. The cable 18 passes around drum 27 and pulleys 24. It is to be noted that the pulleys 24 at the motor end of the device are mounted on a plate 24'' which depends from and is fastened to track member and are offset or displaced with respect to one another so as to prevent crowd-

ing or bunching of the cable 18 on the drum 27. In order to stop the motor when the curtain has reached open or closed position, a limit switch 29 is provided having contacts 30. Gear 31 is mounted on axle 28 and meshes with gear 32 which drives the worm gear construction 33. A contact arm 34 is actuated by the worm gear construction.

In Figure 6 is shown a modified form of 10 motor mounting. In this figure the motor 35 is mounted on a slidable casting which is provided with projections 36 received in slots 37 in track member 4. A spring 38 is mounted in track member 4 and tends to push the 15 motor casting outwardly and so provides a tensioning means for cable 18.

Another means of tensioning the cable is to provide a weighted idler pulley. In order to do this it is necessary to provide two 20 additional pulleys at right angles to idlers 24 but in the same horizontal plane and then hang a weighted pulley on the portion of cable between these two pulleys.

It is to be expressly understood that limit 25 switch 29 may be used with any of the modifications described. Other means of stopping the curtain will readily suggest themselves to those skilled in the art.

It is obvious that I have provided a device 30 that is simple in construction, efficient in operation and practically adapted to various uses in connection with curtains. It is especially adapted for use in connection with theatrical curtains and so may be constructed 35 to save considerable weight, serving admirably for that purpose.

What I claim is:

1. In a curtain supporting apparatus a bracket member having an elongated slot 40 adapted to be connected to a curtain and having a socket at its upper end provided with side flanges and a ball member rotatably mounted between said side flanges.

2. In a curtain supporting apparatus a bracket member having an elongated slot 45 adapted to be connected to a curtain and having a socket at its upper end provided with side flanges and a ball member rotatably mounted between said side flanges, said ball member being mounted upon a horizontal axle.

3. In an apparatus of the character described a track member of hollow construction and rectangular in cross section having 55 a longitudinal slot extending through the bottom side thereof, rails secured to said track member on each side of said slot, a plurality of curtain supporting brackets passing through said slot, each bracket being provided with socket at one end and a ball member rotatably mounted in said socket and engaging said rails.

4. An apparatus of the character described 60 a track member of hollow construction and rectangular in cross section having a longi-

tudinal slot extending through the bottom side thereof, rails secured to said track member on each side of said slot, a plurality of curtain supporting brackets passing through said slot, each bracket being provided with socket at one end and a ball rotatably mounted in said socket and engaging said rails, said ball being mounted on a horizontal axle.

5. In an apparatus of the character described 70 an elongated track member, a plurality of curtain supporting brackets movably mounted on said track member, a motor supported near one end of said track member, pulleys at one end of said track member, operating means between said motor and said pulleys including a worm drive and operating cords connecting said curtain supporting brackets and extending over said pulleys.

6. An apparatus of the character described 75 including an elongated supporting member, a plurality of track members closely associated with said supporting member and supported thereon, each track member having a plurality of rail members therein, a plurality of curtain supporting brackets having 80 means for attachment to a curtain, each bracket having a ball mounted upon a horizontal axle and running upon said rail members and means connecting said brackets for movement longitudinally of said rail members.

7. An apparatus of the character described 85 including an elongated track member, a plurality of curtain supporting brackets movably mounted on said track member, a motor supported near one end of said track member, pulleys at one end of said track member, operating means between said motor and said 90 pulley including a worm drive, operating cords connecting said curtain supporting 95 brackets and extending over said pulleys and automatic means for maintaining said cords under tension.

8. An apparatus of the character described 100 including an elongated track member, a plurality of curtain supporting brackets movably mounted on said track member, a motor supported near one end of said track member, pulleys at one end of said track member, operating means between said motor and said 105 pulley including a worm drive, operating cords connecting said curtain supporting 110 brackets and extending over said pulleys and means for resiliently and slidably mounting said motor so as to provide an automatic tensioning means for said cords.

9. An apparatus of the character described, 115 including an elongated track member, a plurality of curtain supporting brackets, each bracket being provided with a ball adapted to roll on said track member, a motor supported near one end of said track member, pulleys at one end of said track member, operating means between said motor and said 120 pulleys including a worm drive, operating 125 cords connecting said curtain supporting brackets and extending over said pulleys.

cords connecting said curtain supporting brackets and extending over said pulleys and means for resiliently and slidably mounting said motor so as to provide an automatic tensioning means for said cords.

5 10. An apparatus of the character described, including an elongated track member, a plurality of curtain supporting brackets, each bracket being provided with a ball adapted to roll on said track member, a motor supported near one end of said track member, pulleys at one end of said track member, operating means between said motor and said pulleys including a worm drive, 15 operating cords connecting said curtain supporting brackets and extending over said pulleys and automatic means for maintaining said cords under tension.

11. In an apparatus of the character described, a track member of hollow construction and rectangular in cross section, having a longitudinal slot extending through the bottom side thereof, rails secured to said track member on each side of said slot, a 25 plurality of curtain supporting brackets passing through said slot, each bracket being provided with a slot at one end and a pulley member rotatably mounted in said slot and engaging the edges only of said rails so as 30 to provide the minimum amount of friction and insure easy manipulation.

12. In an apparatus of the character described, a bracket member of hollow construction and rectangular in cross section, 35 having a longitudinal slot formed by bending the adjacent portions of said track member inwardly, rails on each side of said slot and secured to said track member by said bent portions, a plurality of curtain supporting 40 brackets passing through said slot, each bracket being provided with a slot at one end, and a ball member rotatably mounted in said slot and engaging said rails.

In testimony that I claim the foregoing, I
45 have hereunto set my hand this 21st day of
August, 1929.

RICHARD R. BRUCKNER.
